UNITED STATES PATENT OFFICE

2,502,840

JIG

Willie Hayes, Pratt City, Ala., assignor to Tennessee Coal, Iron and Railroad Company, a corporation of Alabama

Application March 6, 1945, Serial No. 581,269

2 Claims. (Cl. 209—427)

1

This invention relates to a jig for effecting the separation of mineral substances of different specific gravities and characters.

The invention has among its objects the provision of an improved jig the design of which is such that it operates at substantially maximum efficiency at all times.

A further object of the invention is the provision of a jig having means for automatically feeding material thereto so that the depth of the heavier concentrate is maintained substantially constant in the cell of the jig, whereby overloading of the jig is prevented.

A still further object of the invention is the provision of a jig which insures the delivery of separated material of constant quality.

The above and further objects of the invention will become more apparent in the following description.

The jig of the present invention is useful in the separation of minerals of different specific gravities as, for instance, metal-bearing ores and coal from rock. For the sake of simplicity, the invention will be described in connection with its use in the "washing" of coal, that is, the separation of coal from various impurities such as rock, slate, and the like, but it is to be understood that the invention finds advantages in the separation of other materials, as above indicated.

The invention relates to jigs of the type where in the material to be separated is fed onto a screen in a bath of liquid, and is subjected to rapidly recurring impulses of the liquid through the screen which tend to lift the material and to stratify it in accordance with its specific gravity. The finer, heavier, material passes through the screen and is drawn off from the bottom of the jig as a sludge. The heavier material retained on the screen which, in the case of the washing of coal, is composed of slate and other rocks, is removed from the screen through a rock valve, whereas the lighter material passes over a barrier at the end of the cell. Such type of jig, which is well known, is disclosed in the Elmore patents, Nos. 1,077,876 and 1,327,537.

It has been recognized that for the most efficient operation of jigs of this type it is desirable to retain on the screen of the cell as uniform a depth of concentrates as possible, so that the action of the pulsating liquid upward through the screen and through such bed of concentrates will be uniform. In prior art designs it has been attempted to maintain such uniform depth of concentrates on the cell screen either by manually controlling the rate of feed of material into the

cell and the rate of feed of heavy concentrates, which is rock in a coal washing jig, from the cell, or by manually controlling the rate at which material is fed into the cell and automatically controlling the rate of discharge of rock from the cell in accordance with the depth of the rock bed on the screen. Such latter arrangement is shown in Elmore Patent No. 997,609.

Such methods of controlling the cell have worked fairly satisfactorily where the composition of the material fed into the cell has stayed within fairly close limits. Such a condition is met, for instance, when coal mined from a vein of substantial thickness is hand-loaded at the mine face, since such hand loading excludes, to a large extent, pieces of rock and slate. Where, however, the composition of the material varies considerably and changes in the composition of the material being fed occur very rapidly, such methods of control are not satisfactory due to the operator's inability to appreciate the need for a change in rate of in-feed before the harm has been done. It has been found that where coal is mined from a relatively thin vein and the coal is mechanically loaded at the mine face, such coal is apt to contain large amounts of rock and the rock content is apt to vary considerably from time to time. If, because of such rapid change in composition, the depth of rock in the cell becomes so high that the capacity of the rock valve is exceeded, the cell no longer separates completely the lighter from the heavier materials and certain amounts of such heavier materials are washed over with the lighter separated portions.

The present invention provides a jig which overcomes these difficulties and produces a product of uniform quality regardless of the rock content of the in-fed material or of the rapidity of change of such content. Such objects are accomplished by the provision of means automatically controlling the height of the rock bed in the jig cell by varying the rate of in-feed of the coal, thereby avoiding the possibility of overloading the jig. At the same time, however, the jig is kept working at full capacity and therefore at its maximum efficiency.

The invention will be more readily understood by reference to the accompanying drawings, in which:

Figure 1 is a view in side elevation of a coal washing jig made in accordance with the present invention;

Figure 2 is a view in plan of the jig shown in Figure 1;

Figure 3 is a view in transverse cross-section

Figure 8 is an enlarged view of another portion of the door-positioning limit switch;

Figure 9 is a schematic view of a portion of the rock discharge valve operation mechanism; and

Figure 10 is a schematic wiring diagram of the electrical control for jig of the present invention.

The jig illustrated in the drawings consists of three cells serially arranged. The first cell, designated by the reference character 2, is fed with the raw coal to be washed, and discharges the lighter of the separated materials into the second cell 4 which in turn discharges the lighter of the materials separated in it into the third and final cell 6. Each of the cells is provided at the sides thereof, as shown in Figure 3, with four eccentrically actuated plungers 8 which reciprocate in vertical plunger chambers 10. Such plungers impart a series of surges or vibrations to the water with which the cell and the plunger chambers are filled, whereby the water intermittently rises and falls through the screen floor of each cell and through the bed of material supported by such screen. The screen in the first cell is designated by the character 12. Such vertical motion of the water in the cell accomplishes the washing out of the fine heavy particles from the material, which particles fall through the screen into the bottom or hutch 14 of the cell, from which they are discharged through hutch valve 16.

Plungers 8 are driven by means of a horizontal drive shaft 18 which in turn is driven by a motor through the medium of a motor pinion meshing with the large gear on the end of shaft 18, as shown in Figure 2. Bevel pinions 20 and 21 are affixed to shaft 18 in position to mesh with pinions 22 and 23, respectively, on the longitudinal eccentric shafts 24 and 26, respectively, above plunger chambers 10. Eccentrics on shafts 24 and 26 are connected to plungers 8 and provide for the vertical reciprocation thereof.

The rapidly repeated surges of the water upwardly through the bed of the material on the screen stratifies the material into the lower, heavier, layer of rock R, and the upper lighter, more buoyant, layer of coal C, as shown in Figure 4. The feed of material into the cell at the left-hand end thereof tends to make such bed of greater depth at such point, the bed levelling out as it travels gradually to the right. The rock layer R remains in contact with the screen and gradually travels into the rock valve pocket 32, whence it is fed into the generally star-shaped rotary rock valve 34 which discharges it into chute 36 leading to a refuse flume, when each pocket in the valve reaches its lower position. The lighter layer of coal C, on the other hand, is

progressively washed up and over end barrier 28 at the right-hand end of the cell and down inclined chute 30 into the succeeding cell 4. It is to be understood that separation of the coal from the rock is not complete in the first cell, which explains the use of the two subsequent cells, but that usually some rock is washed over the barrier into the second cell, as shown in Figure 4 of the drawings. With the 3-cell jig as shown, the material discharged from the rock valves of the first two cells is refuse, whereas that discharged from the rock valve of the third cell 6 is low-quality coal employed as boiler coal; the lighter material finally discharged from the third cell is high-quality washed coal which may be employed, for instance, in the making of coke.

It will be apparent from the above that if the rock layer R in the first cell has a thickness in excess of that desired and consequently a discharge rate materially in excess of the capacity of the rotary rock valve of the first cell, large quantities of rock will be washed over barrier 28 of the first cell, into the second cell, and that as a consequence, the second cell will be overburdened, and the discharge from the rock valve of the third cell may have an unduly high rock content. There will also be the further possibility of the presence of some rock in the lighter discharged material from the third cell.

The rock valves 34 of the first cell, as well as those of the succeeding two cells, are driven by ratchet drive devices indicated generally at 38 in Figure 2. Such ratchet drives are driven by means of a vertical shaft 40 shown in Figure 2, which is driven off shaft 18, shaft 40 in turn driving a lower transverse shaft 42 to one end of which is affixed a crank 44. Pitman 46 connected to crank 44 effects the oscillation of ratchet drive 38 of the first cell, and pitmans 47, which extend between the ratchet drive means of the first, second, and third cells, drive the rock valves of the two latter cells. Adjustment of the rate at which the rock valves are driven is accomplished by means of adjusting wheels 48 by which the length of the ratchet arm of the particular ratchet drive of which it is a part may be varied.

In accordance with the present invention, the first cell 2 of the jig is provided at the left, as shown in Figures 1 and 2, with a coal bin 50 into which the coal to be washed is fed. The lower portion of the coal bin is provided with a power-driven revolving feeder 52 equipped with radial projections which pick the coal up and discharge it into the first cell. Coal thus discharged impinges upon angular deflecting plate 54 positioned in the first cell, as shown. Control of the rate at which coal is fed from the bin to the rotary feeder is effected by means of a vertically slideable bin closing gate 56, which may be adjusted by means of racks 58 affixed thereto, such racks meshing with pinions 60 on transverse shaft 62. Rotation of the shaft and consequent adjustment of the bin gate is accomplished by means of hand-wheel 64. The control of the rate of feed accomplished by gate 56 is in the nature of a rough adjustment, and once made, gate 56 may be left in the desired position.

Control of the rate of feed to the first cell within the limits necessary to effect automatic feeding of the jig is accomplished by means of door 66 cooperating with the revolving feeder 52, said door being mounted, as shown, on a swinging frame pivoted about a shaft 62, whereby the free space between the revolving feeder and the

lower end of the door may be varied. Such swinging of frame 68 is effected, in the modification of the apparatus shown, by means of a gear motor 70 mounted on a platform supported on beams above the first cell 2. Driven shaft 72 of the gear motor is connected to a vertical screw 73 journaled in lower bearing 74 and in an upper bearing 76 on top of the door-positioning limit switch box 77. Screw 73 is composed of a lower portion 78 of substantial diameter, which effects the adjustment of frame 68, and an upper portion 80, shown in Figure 6, of somewhat smaller diameter. Nut 82 on lower screw portion 78 is provided with transverse arms 84 which slide in vertical guideways 86. The swinging frame 68 is provided with a door-operating arm 88 having an outer forked end, the arms of such fork having slots 90 therein for the reception of arms 84 of nut 82. Such structure makes possible the lowering or raising of the door 66, as required, by gear motor 70, such motor, in turn, turning screw 78, thereby raising or lowering arm 88 depending upon the direction of rotation of the motor.

The door operating mechanism is automatically operated in accordance with the height of the rock bed R in the first cell of the jig by the following mechanism acting in conjunction with the door-positioning limit switch device in switch box 77. A "float" 111, which rests upon the top of the rock bed R and is preferably of streamlined shape to facilitate the flow of material past it, is mounted on the bottom end of float rod 112. Such float rod is positioned and guided for vertical movement by means of guide rollers 113, which are supported over the cell by means not shown. The float is held in contact with the top of the rock bed at a location where the bed tends to be level, with the desired amount of pressure by means of counterweights 115 held in counterweight holder 114 at the upper end of the float rod. The rock level indicating switch, which is actuated by float rod 112, is shown in detail in Figure 5. Switch box 116, through the bottom and top of which float rod 112 extends, has mounted thereon on one side of the float rod an elongated bus bar 118 and on the other side of the float rod an insulating plate 119 which mounts the contacts labeled FL3, FL2, FL1, FR1, FR2, and FVC. The first five of these contacts are, as shown, of short extent, whereas the lowest, FVC, is of considerable length. The upper surfaces of such contacts are substantially flush with the top surface of the insulator 119, to enable the contact arm 117 which is mounted upon float rod 112 by an insulating bushing 117', to ride freely thereover while still making contact therewith as the float rod rises and falls. Vertical adjustment of arm 117 with respect to the float rod may be made by means of the set screw 118' in the insulating bushing 117' upon which arm 117 is mounted. It will be apparent that such switch structure provides a means whereby the circuit is closed between bus bar 118 and any one of the various contacts FL3, etc., only when contact arm 117 touches one of the contacts.

The structure of the door-positioning limit switch mechanism in switch box 77 is shown more fully in Figure 6. As there shown, the switch is in the neutral position, corresponding to the normal or neutral position of the rock level contact arm 117 shown in Figure 5. The switch-operating arm 94 is threadedly engaged with the screw 80 so as to be raised and lowered in accordance with the motion of door-operating nut 82. Rotation of arm 94 is prevented by the pro-

tection of a rearwardly directed arm 96 attached thereto, said latter arm having a sliding engagement with the vertically fixed guide rod 98 positioned in the switch box. Arm 94 is provided with a series of vertically-extending switch-operating fingers 100, 101, 102, 103 and 104, said fingers being adjustable vertically of arm 94 and retained therein by means of set screws, as shown. Each of the switch-operating fingers is provided with an inclined forward end, as more clearly shown in Figures 7 and 8, for the operation of the microswitches.

The switch 2D, shown in Figure 7, is typical of switches 1D, 2D, and 3D, whereas switch 1U, shown in Figure 8, is typical of switches 1U and 2U. Switch 2D has a switch element 105 which is held in raised circuit-breaking condition by a spring member 106 when switch-operating finger 101 is in the lower position shown by the dotted line. When such switch member is advanced vertically, however, as shown in full lines, it contacts roller 107 and depresses the switch member in order to complete the electric circuit through the switch.

The switch 1U, however, which is provided with switch element 108, is of such construction that it is closed when the switch-operating finger 103 is positioned in the lower full line position shown. When member 103 is advanced upwardly to the dotted line position, it engages roller 110 on the end of spring 109, thereby depressing the switching element and breaking the electric circuit through the switch.

The door positioning limit switch functions, as will be more clearly apparent in considering the wiring diagram in Figure 10, to stop operation of the door adjusting motor 70 when the door has reached a predetermined position depending on the position of the float 111. The door-positioning limit switch accomplishes this by breaking its particular contact through which the control circuit energized by closing of the float contact is completed, when the door reaches the required position. It will be obvious from a consideration of Figure 6 that limit switch 1D opens at the first door position below normal, and that limit switches 2D and 3D operate similarly at the second and third positions, respectively, below normal. Limit switches 1U and 2U open at the first and second positions, respectively, above normal. Each limit switch opens and remains open as long as the door is at or past that particular position away from the normal position of the door.

The operation of the automatically controlled feeding device for the jig thus far described will be more fully understood by reference to the schematic wiring diagram shown in Figure 10, in which the door-positioning limit switches are all shown closed, and the rock level contacts are all shown open, as they are when the rock level is of normal height and the door is in its normal position. The door-positioning motor 70 is caused to raise or lower the door whereby the mechanism tends to hold the rock level in the first cell such that the contact arm 117 normally lies between contacts FL1 and FR1. Such position, which is called the normal or neutral position, is attained when the height of the rock bed in the cell is at its optimum value. When arm 117 is within such range and touching neither contact FL1 nor FR1, motor 70 is at rest and the door is held in fixed position. If, however, the height of the rock bed should rise sufficiently to bring contact arm 117 into position to touch contact FL1, motor 70 is actuated to lower the door to correct such condi-

tion and to bring the height of the rock bed back to its normal value. If the rock bed level rises still further, however, switch FL2 operates to cause motor 70 to lower the door still further. Switch FL3 is effective, when the rock level rises sufficiently to cause it to complete the circuit, to operate motor 70 to close the door still further to correct the condition. If the level of the rock bed falls, on the other hand, so as to cause contact arm 117 to touch contact FR1, motor 70 is caused to rotate in such direction as to raise the door to admit more coal, and thus to correct the condition and bring the rock level back to normal. Upon further fall of the rock bed level, however, should such occur, switch FR2 is operated to raise the door still further. If the rock level should, in spite of this, fall to such point that arm 117 touches contact FVC, the ratchet feed mechanism 38 for the first cell is caused to be ineffective, by a means subsequently to be described, whereby rotation of the rock valve 34 is stopped. It will be apparent that each of the various switches FL1, FL2, FL3, FR1, FR2, and FVC closes the circuit, thereby operating motor 70, only when contact arm 117 touches that particular contact.

The motor 70 is supplied from an appropriate three-phase alternating current source to which are connected the three lead wires L1, L2, and L3. Such source of current, besides supplying motor 70, is employed to energize the six relays, 1L, 2L, 3L, 1R, 2R, and VC, corresponding to the six contacts, FL1, etc., and also to energize the two operating coils of the reversing contactor RC. The reversing contactor RC is a conventional device having two operating coils 136 and 137 which, when operated selectively, establish contacts for operating the motor in opposite directions. The contactor is of such construction that neither of such operating coils is energized when the contactor is in neutral position, and the circuit to the motor is broken and the motor is stopped.

The wiring diagram will be more readily understood by tracing the circuits therethrough which are utilized when the rock bed in the first cell of the jig rises progressively from the normal level so as to close switches FL1, FL2, and FL3 successively, and also the circuits which are energized when the rock bed level falls from the normal level so as to close switches FR1, FR2, and FVC, successively.

First, assuming that the rock bed level has risen from normal to a point sufficiently to allow contact arm 117 to touch contact FL1, motor 70 is actuated in a direction to lower the door, thereby decreasing the rate of feed of coal into the jig. Such actuation is accomplished by the connection of one side of the actuating coil 126 of relay 1L to line L1 through wire 128, wire 122, closed switch FL1, and wire 123, and by the connection of the other side of coil 126 to line L3 through wires 131 and 130, closed limit switch 1D, and wire 128.

Energization of relay coil 126 closes its contacts 132 and 134, thereby energizing coil 136 of the reversing contactor RC in the following manner:

Current travels from lead L3 through wires 138, 139, 140, 142, and 144 to one side of coil 136, and from lead L1 through wires 120, 122, and 149, contact 134, wire 151, contact 204, and wire 152, to the other side of coil 136. Thereupon the reversing contactor RC is thrown to close its contacts 154, 156, and 158 and to open normally closed contact 160. The wires T1, T2, and T3 of motor

70 are then connected to lines L3, L2, and L1, respectively, as follows:

From lead L1 current flows to wire 162, wire 164, through contact 158, to wires 166 and 167, and thence to wire T3 of the motor. Current flows from lead L2 to wires 168, wire 169, through contact 156, to wire 170 and thence to wire T2 of the motor. Current flows from lead L3 to wire 138, wire 139, through contact 154 and wires 172 and 174 to line T1 of the motor. The motor operates to lower the door until operating finger 102 of the door-positioning limit switch is lowered sufficiently to allow the opening of switch 1D. This breaks the circuit to relay 1L, the coil 136 of the reversing contactor is de-energized, the reversing contactor goes back to its neutral position, and the motor 70 stops.

If the rock bed level in the first cell of the jig continues to rise, contact arm 117 passes contact 201, and if the rise continues, the arm touches contact FL2. When such contact is made, relay 2L is energized as follows:

Current flows from lead L1 through wires 120 and 122, contact FL2 and wire 176, to one side 25 of the operating coil 177 of relay 2L. Current flows from lead L3 through wire 131, wire 130, closed limit switch 2D, and wire 178, to the other side of coil 177.

Energization of relay-operating coil 177 closes its contacts 180 and 182, thereby energizing coil 136 of the reversing contactor in the following manner:

Current flows from lead L1 through wires 120, 122, 183, 181, contact 182, and wires 150, 151, 35 switch 204, and wire 152 to one side of coil 136. The other side of such coil is supplied from lead L3 through wires 138, 139, 140, 142, and 144. Operating coil 136 then throws the reversing contactor and operates motor 70 in the same direction as before, to lower the gate. Such operation of the motor continues until limit switch 2D is opened by the fall of operating finger 101, at which time the relay 2L is deenergized, the reversing contactor returns to neutral, and the motor stops.

The same sequence of operations follows, should the rock bed level in cell 2 rise sufficiently for contact arm 117 to touch contact FL3. In such case, operating coil 212 of relay 3L is energized with current from lead L1 through wires 120, 122, closed switch FL3, and wire 210 and from lead L3 through wires 131, 130, closed limit switch 3D, and wire 214.

Upon energization of coil 212 of relay 3L, contacts 216 and 218 of the latter are closed, and operating coil 136 of the reversing contactor is energized as follows:

Current flows from lead L1 through wires 120, 122, 183, 181, 184, 185, contact 218, wires 220, 150, 60 151, switch 204, and wire 152 to one side of coil 136. The other side of such coil is supplied with current from lead L3 through wires 138, 139, 140, 142, and 144. Coil 136 again operates the reversing contactor to establish connections so that motor 70 rotates in such direction as to lower the door, and the motor is stopped upon the opening of limit switch 3D and the consequent deenergization of relay 3L.

Assuming now that the rock bed level has been 70 normal but has fallen to a level such that contact arm 117 touches contact FR1, motor 70 is operated in the opposite direction, to raise the door, thereby to admit coal at a faster rate and correct such condition. In such case operating coil 222 of relay 1R is energized as follows:

Current flows from lead L1 through wires 120 and 122 through closed switch FR1, and through wire 188 to one side of coil 222. The other side of such coil receives current from lead L3 through wires 131, 130, closed limit switch 1U, and wire 189.

Energization of coil 222 closes contacts 190 and 192 of relay 1R, thereby energizing operating coil 197 of the reversing contactor RC. Coil 197 is energized as follows:

Current flows from lead L1 through wires 120 and 122, closed contacts FR1, wire 188, contact 190, and wires 224, contact 192, wire 194, switch 160 and wire 196, to one side of coil 197. The other side of such coil receives current from lead L3 through wires 138, 139, 140 and 142. Energization of operating coil 197 causes the reversing contactor RC to be thrown in such direction as to close switches 198, 200, and 202 and to open normally closed switch 204. Leads L1, L2, and L3 will now be connected to motor wires T1, T2, and T3, respectively, thereby operating the motor 70 in the reverse direction and causing the door to rise. Connection of the motor to the current source leads is effected as follows:

Current flows from lead L1 through wire 162, switch 202, and wire 174 to wire T1. Current flows from lead L2 through wire 168, switch 200, and wires 121 and 170, to wire T2, and current flows from lead L3 through wire 138, switch 198, and wires 125, 166, and 167 to wire T3. Rotation of the motor 70 to effect opening of the door continues as long as switch FR1 and limit switch 1U are closed, and stops when either opens. Normally actuation of the motor is stopped by the opening of limit switch 1U by the rise of operating finger 103.

If the rock level in the first cell 2 continues to fall, however, contact 117 will touch contact FR2 to energize relay 2R and again operate motor 70 in such direction as to raise the door. When this occurs, operating coil 228 of relay 2R is energized by means of current flowing from lead L1, through wires 120, 122, closed switch FR2, and wire 226 to one side of coil 228. The other side of such coil receives current from lead L3 through wires 131, 130, closed limit switch 2U, and wire 229.

Energization of coil 228 of relay 2R causes closing of its contacts 230 and 234, thereby energizing operating coil 197 of the reversing contactor as follows:

Current flows from line L1 through wires 120 and 122, closed contacts FR2, wires 226, 230, and 232, contact 234, wires 236 and 194, contact 160 and wire 196, to one side of coil 197. The other side of such coil receives current from lead L3 through wires 138, 139, 140, and 142. Motor 70 is thus operated again in such direction as to raise the door, and operates until either switch FR2 or limit switch 2U is broken.

If the rock level in the cell should continue to fall, contact arm 117 will touch contact FVC. The closing of switch FVC operates relay VC in the following manner:

Current flows from lead L1 through wires 120, 122, closed switch FVC, and wire 206 to one side of the operating coil 238 of the relay VC. The other side of such coil is supplied with current from lead L3 through wires 131, 240, and 208. Energization of coil 238 of the relay closes its contact 242, thereby energizing the pawl-lifting solenoid 248 of the ratchet feeding device subsequently to be described, which is supplied with current from a separate current source,

L4 and L5. Current then flows in the pawl-lifting solenoid circuit from line L4 through wire 244, contact 242, wire 246, through solenoid coil 248, and back to lead L5.

Energization of solenoid coil 248 lifts the driving pawl of the ratchet mechanism shown in Figure 9 through which the rock valve 34 of the first cell is driven. Thereupon discharge of rock from the first cell ceases, and remains stopped so long as switch FVC is closed, thereby allowing the level of the rock in the cell to build up. As shown in Figure 9, the ratchet drive mechanism for the rock valve consists of an arm 250 pivoted about the rock valve shaft 252 and operated by pitman 46, above described. Drive pawl 256, pivoted as shown on arm 250, coacts with ratchet wheel 254 affixed to the valve shaft in such a manner as to cause intermittent rotation of the valve upon oscillation of arm 250. To prevent turning of the ratchet wheel 254 in a reverse direction, there is provided a spring-pressed holding pawl 258 attached as shown to a projection 260 on the side of the first cell near the location of the rock valve.

Energization of solenoid 248, which is attached to the upper end of arm 250 by a clamping means shown generally at 262, attracts the armature 264 attached to the upper surface of pawl 256 thereby pulling the pawl free of the ratchet teeth on ratchet wheel 254 and stopping rotation of the rock valve.

The apparatus of the present invention above described therefore automatically insures the maintenance of the rock bed level of the first cell within such limits as to insure the optimum operation of the first cell of the jig, and prevents the undue contamination of the lighter material carried over from the first cell with rock or other heavier material which would occur if such rock bed should rise to an undesirably high level. Thus the two latter cells may continue the separation of the material in the most efficient manner. The apparatus is automatic in its operation, and functions to its fullest capacity while producing coal of uniform quality, regardless of the amount or rapidity of change of the rock content in the raw infed material.

It is to be understood that the apparatus of the present invention is capable of numerous variations obvious to one skilled in the art, and that its scope is to be defined by the appended claims.

I claim:

1. A jig for separating materials of differing specific gravity comprising a cell adapted to contain liquid, mechanism for feeding solid materials to said cell and including a gate which has a plurality of positions of adjustment, pulsing mechanism for stratifying solid materials in said cell according to their specific gravities, upper and lower discharges for removing materials from the upper and lower strata respectively, and control means for adjusting said gate by predetermined increments to its different positions of adjustment in accordance with incremental changes in the stratification level, said control means including a float adapted to remain at the stratification level, a reversible electric motor, a mechanical linkage connecting said motor and said gate, and electric circuits for energizing said motor and having a plurality of sets of contacts one set of which is closed when said float rises or sinks an incremental 75 distance with change in the stratification level,

said circuits having normally closed limit switches corresponding with the different positions of adjustment of said gate, said mechanical linkage opening the limit switch in the energizing circuit when said gate reaches a predetermined position of adjustment corresponding with the stratification level of the particular set of contacts which are closed by said float, said gate thus remaining stationary until a change in the quality of the feed changes the stratification level by an incremental distance of a magnitude sufficient to close a different set of said contacts.

2. A jig for separating materials of differing specific gravity comprising a cell adapted to contain liquid, mechanism for feeding solid materials to said cell and including a gate which has a normal opening but is adjustable by fixed increments for varying the feed rate, pulsing mechanism for stratifying solid materials in said cell according to their specific gravities, upper and lower discharges for removing materials from the upper and lower strata respectively, and control means for regulating the opening of said gate and thereby varying the feed rate by fixed increments in accordance with incremental changes in the stratification level, said control means including a reversible electric motor, a linkage operatively connecting said motor and said gate, a float within said cell adapted to remain at the stratification level and having a neutral position, an electric circuit for operating said motor to decrease the gate opening to less than its normal opening and having a set of contacts which close as said float rises a fixed distance above its neutral position, an electric circuit for operating

said motor in the opposite direction to increase the gate opening to more than its normal opening and having a set of contacts which close as said float sinks a fixed distance below its neutral position, a limit switch in the first circuit which is closed when said gate is at its normal opening and opened by said linkage when said gate has closed an incremental distance therefrom, and a limit switch in the second circuit which is closed when said gate is at its normal opening and opened by said linkage when said gate has opened an incremental distance therefrom, said limit switches automatically closing as said gate approaches its normal opening, the motor circuits remaining open and the gate stationary after each gate movement until the quality of the feed changes sufficiently to change the stratification level by a full increment.

WILLIE HAYES.
